UNITED STATES PATENT OFFICE.

GEORGE H. GEORGELIS, OF FORT SCREVEN, GEORGIA.

SUBMARINE-DESTROYER.

1,296,646.

Specification of Letters Patent. Patented Mar. 11, 1919.

Application filed February 6, 1918. Serial No. 215,639.

To all whom it may concern:

Be it known that I, GEORGE H. GEORGELIS, a citizen of the United States, and a resident of Fort Screven, in the county of Chat-
ham and State of Georgia, have invented a certain new and useful Improvement in Submarine-Destroyers, of which the following is a specification.

The present invention relates to ships, and 10 more particularly to those of the submarine type.

The object of the present invention is to provide a submarine water craft of a construction adapted for use as a destroyer of 15 submarine craft; a device capable of attaining relatively high speed in travel, particularly when submerged; a craft which is relatively simple and strong in construction; and a craft which may be driven at a high 20 rate of travel with a minimum speed of operation of its parts.

Another object of the present invention is to provide a submarine craft having an exterior hull or shell which is continuous and 25 adapted to rotate about the car or body of the craft, and which is driven for impelling the craft through the water at a high rate of speed by exterior spiral fins upon the hull; and which is provided with means for 30 holding the hull in various positions of rotation to enable the retention of any punctured or injured portion of the hull at the top of the craft so that the craft may be raised to the surface level of the water and 35 propelled by other means provided to a place of safety and repair.

The invention also embodies the provision of a connecting shaft or axle which pivotally connects the hull to the car or body of the 40 craft and which is provided at its forward end with an impact point of hard steel or the like resiliently connected to the shaft for absorbing shock incident to the striking of the point against other submarines or 45 other obstacles.

The above, and various other objects and advantages of this invention will be in part described and in part understood from the following detailed description of the present 50 preferred embodiment of this invention, the same being illustrated in the accompanying drawings, wherein:

Figure 1 is a side elevation of a submarine craft constructed according to the present 55 invention.

Fig. 2 is a longitudinal vertical section

taken through the same, disclosing the mounting of a wireless antennæ detachably upon the exterior of the hull when the craft is raised 60 to the surface level of the water.

Fig. 3 is a transverse section through the craft, taken on the line 3—3 of Fig. 2.

Fig. 4 is an enlarged transverse section taken on the line 4—4 of Fig. 2, showing the 65 connection between the hull, the shaft and the point.

Fig. 5 is a detail, enlarged fragmentary section through the rear end of the hull and the shaft, showing the mountings of the propeller and the rudder, and the brake for arresting the rotation of the hull.

Fig. 6 is a fragmentary enlarged section taken horizontally through the craft and looking down upon the drive connection between the engine and the hull.

Fig. 7 is a fragmentary enlarged section taken through the hull and the car, showing the connection between the same and taken on the line 7—7 of Fig. 3.

Fig. 8 is a fragmentary enlarged section taken through a portion of the hull and disclosing one of the hatch doors through which men and supplies may pass.

Referring to the drawing by numerals, 10 designates the hull or shell of the craft of preferably oblong contour with tapering ends adapted to pass freely through a body of water. The hull 10 is provided with a number of spiral ribs or fins 11 upon its 15 exterior surface which extend from end to end of the hull. Arranged axially within the hull is a hollow tube or shaft 12 mounted for rotation at its opposite ends in the front and rear ends of the hull and provided at 20 its forward end with a closure plug 13 within the outer end of which is slidably mounted an impact point 14, the latter being cushioned within the plug 13 by a spring 15. Impact against the point 14 is absorbed to 25 a considerable extent through the spring 15 so that injury to the shaft 12 and hull 10, and the parts carried thereby is practically 30 eliminated.

Suspended from the hollow shaft 12 by 35 straps 16 is a body part or car 17 having an upper deck or platform 18 lying substantially within the horizontal plane of the longitudinal axis of the shaft 12. This body or car 17 may be divided into a plurality 40 of compartments as shown in Fig. 3, and is adapted to contain stores and the like for use in handling and manipulating the craft.

At one or more points throughout the length of the craft, means is provided for anchoring the body 17 to the hull 10. As shown, the means comprises spaced apart 5 inwardly offset rails 19 arranged in pairs and extending annularly about the inner surface of the hull 10 and providing an underlying slot or way to receive rollers 20 carried by brackets 21 upon the bottom and 10 sides of the car 17. These rollers 20 are mounted upon T-shanks the branches of which engage the rollers and project beneath the rails 19. The rollers 20 travel in the annular ways as the hull is rotated and prevent 15 the body 17 from shifting longitudinally upon or with the shaft 12.

A periscope 22, or the like may be mounted upon the plug 18 and is provided with a sight tube 23 extending through the plug to 20 the interior of the hull. The hull may thus rotate about the shaft and plug without disturbing the position of the periscope. As shown in Fig. 4, the hull 10 is preferably mounted directly upon a plurality of rollers 25 24 constituting bearings between the hull and the shaft 12.

The rear end of the hull has an inwardly extending drum 25 surrounding the rear end of the shaft and forming, practically, a continuation of the hull, a packing gland 26 being forced into a suitable opening in the drum 25 and surrounding the shaft to pack the same in the hull. A brake band 27 surrounds the drum 25 and is operable, through 30 a link 28 by a hand lever 29 supported upon the platform 18 of the body. The brake may be manipulated to hold the hull in any desired position of rotation.

For the purpose of turning the hull 10 about the body, a suitable motor or engine 30 may be employed, the engine being mounted upon the deck 18 and having a crank shaft 31 projecting forwardly from the engine and provided with a worm 32. A worm wheel 33 meshes with the worm and is carried on a shaft 34 extending transversely within the hull and coupled, by bevel pinions 35 to counter shafts 36 provided with driving pinions 37 meshing with an internal rack or 40 gear wheel 38 secured to the inner surface of the hull 10. The engine 30 has its shaft 31 projecting rearwardly and connected by shafting and universal joints, such as indicated at 39, to a propeller 40 of the screw type for driving the craft when the hull is held from turning. Suitable clutches or the like may be interposed between the engine and the hull, and the engine and the propeller.

At a suitable point upon the car or body 45 17 is a tiller wheel 41 connected by shafting 42 and bevel gears to a rudder 43 hinged upon the rear end of the hull and adapted to be used for controlling the movements of the craft in the water.

The car 17 is provided with one or more guns 44 adapted to be swung into position through hatchways 45 formed in the hull and closed by inwardly opening doors 46. The doors 46 are provided with packing 70 strips 47 of hard rubber or the like adapted to seal the doors in the hull when closed. The doors 46, as shown in Fig. 8, are formed to bind in the hull when the doors are swung outward, and also by centrifugal force incident to the rotation of the hull. The hull is provided at suitable points with bracing rings 48 to strengthen the hull and which preferably are annular in form and secured to the inner wall of the hull. The hull may 80 be provided at one or more sides with pairs of spaced sockets 49 to receive staffs 50 adapted to support a wireless antennæ 51 when the craft is lying adjacent the surface level of the water. Searchlights 52 are 85 detachably mounted upon the exterior of the hull at hatchways 53 formed in the hull and which may be of the construction shown in Fig. 8. Wires 54 lead from a battery or exciter 55 carried upon the body 17 for supplying current to the searchlight 53. The searchlight 52 and the staffs 50 are withdrawn from the hull and deposited in the body 17, and the gun 41 is lowered to the body 17 prior to submerging and to admit 90 free rotation of the hull about the body.

It is thought that the operation of the craft will be readily understood from the above, for when the detachable parts are taken within the body, the latter may be 100 submerged by any of the well known means, and the brake 27 released and the engine 30 set in motion for turning the hull.

It is of course understood that various changes and modifications may be made in the details of construction and design of the above specifically described embodiment of this invention without departing from the spirit thereof, such changes and modifications being restricted only by the scope of 110 the following claims.

What is claimed is:

1. In a submarine, the combination of a body part, a hull pivotally connected to and surrounding the body part, means on the body part connected to the hull for revolving the latter, doors hinged in the wall of the hull and opening inwardly and adapted to be urged into closed position by centrifugal force incident to the rotation of the hull, and means for propelling the submarine when the hull is stationary.

2. In a submarine, the combination, of a body part, a hull surrounding and pivotally connected to the body part, a motor on the body part, means connecting the motor and the hull for rotating the hull by the rotation of the body part, a brake collar carried upon the hull, a brake band surrounding the brake collar, means carried by the body 130

part for operating the brake band to arrest rotation of the hull, doors hinged in the wall of the hull and opening inwardly and adapted to be urged into closed position by 5 centrifugal force incident to the rotation of the hull.

3. In a submarine, the combination, of a body part, a hull pivotally connected to and surrounding the body part, means on the 10 body part connected to the hull for revolving the latter, doors hinged in the wall of the hull and opening inwardly and adapted to be urged into closed position by centrifugal force incident to rotation of the hull.

15 4. In a submarine, the combination, of a body part, a hull pivotally connected to and surrounding the body part, means on the body part connected to the hull for revolving the latter, doors hinged in the wall of the 30 hull and opening inwardly and adapted to be urged into closed position by centrifugal force incident to rotation of the hull, packing strips carried by the edges of the 35 doors to form fluid tight joints between the doors and hull.

hull and opening inwardly and adapted to 20 be urged into closed position by centrifugal force incident to rotation of the hull, a plurality of annular trackways carried in the hull, and a plurality of rollers, yieldably supported by the body and engaging said 25 trackway.

5. In a submarine, the combination, of a body part, a hull pivotally connected to and surrounding the body part, means on the body part connected to the hull for revolving the latter, doors hinged in the wall of the hull and opening inwardly and adapted to be urged into closed position by centrifugal force incident to rotation of the hull, 30 packing strips carried by the edges of the doors to form fluid tight joints between the doors and hull.

GEORGE H. GEORGELIS.
